ENGINE STARTER JAW MESHING
MECHANISM

Richard E. Sears, Cleveland Heights, Ohio, assignor to Jack & Heintz Precision Industries, Inc., Cleveland, Ohio, a corporation of Delaware

Application March 10, 1950, Serial No. 148,889

9 Claims. (Cl. 74—6)

1

This invention relates in general to engine starters and more particularly to improvements in means for meshing the starter jaw with the engine jaw.

One of the primary objects of my invention is to provide such a jaw meshing device that will insure a smooth positively interlocked engagement of the complementary jaws of the starter and engine and avoid end abutment of the teeth of the jaws and resulting chattering without full drive engagement.

Another object is to provide such a device that will insure such proper mesh before full rotational power is applied by the starter motor to the starter jaw.

Another object is to provide in such a device a starter jaw extension means that is operable to extend the starter jaw into partial engagement with the engine jaw prior to rotation of the starter jaw and a separate means operable upon initial rotation of the starter motor to positively extend the starter jaw home into the engine jaw before rotation of the starter jaw.

Another object is to provide such a starter jaw extension means that is solenoid operated to linearly extend the starter jaw into partial engagement with the engine jaw and a separate means, operable by rotation of the starter motor, which in turn occurs after a predetermined operation of the solenoid, to positively extend the starter jaw home into the engine jaw before rotation of the starter jaw.

With the foregoing and other objects in view, the invention resides in the combination of parts and in the details of construction, hereinafter set forth in the following specification and appended claims, certain embodiments thereof being illustrated in the accompanying drawings, in which:

Figure 1 is a view in longitudinal section taken through the starter and the engine jaw shown unmched with the starter jaw;

Figure 2 is a view in side elevation of the jaws of the starter and engine shown in partial mesh and the starter jaw cam slightly rotated from the relative position of Figure 1;

Figure 3 is a view similar to Figure 2, showing the two jaws meshed and the starter jaw into mesh with the engine jaw;

Figure 4 is a schematic wiring diagram for the engine starter; and

Figure 5 is a view in perspective of the starter jaw operating cam.

Referring more particularly to the drawings, the engine starter may include a main housing 1 for an electrical motor, the rotary armature 2

2

of which is carried by a shaft 3 that is mounted to rotate in bearings 4 and 5. On the front, or right, end of shaft 3 is formed a sun gear 6 that meshes with planetary gears, such as shown in Figure 1 at 7. Each of the planetary gears mesh with alternate internally toothed plates of a stack of friction plates forming the conventional torque release device 8. Each of the planetary gears 7 is mounted to rotate about a pin 9 and thus secured to a planet carrier 10 that extends forwardly in the form of a barrel 11. The barrel 11 is mounted for rotation in bearings 12 and 13 in a housing 14 removably secured to a main housing 1 by bolts 15. Thus, as long as the torque release 8 permits, the sun gear 6 rotates the planet carrier 10 which causes the barrel 11 to rotate.

Barrel 11 is provided with internal longitudinal splines and the hollow barrel of the starter jaw 16 is provided with external longitudinal splines of lesser width than the internal splines of the barrel 11 to engage the same with lost motion, the purpose of which is to be later described in detail. Arranged behind, or to the left of, the starter jaw is a hollow operating cam 17 that is provided with external longitudinal splines that are wider than those of the starter jaw to engage, without lost motion, the internal splines of the barrel 11.

Inside of the hollow starter jaw 16 and cam 17 is inserted a cup 18 with a flange 19 and extending through the cup and secured to the starter jaw is a solenoid rod 20 having a spring retainer plate 21 to hold in compression, between plate 21 and the bottom of the cup, a coil spring 22.

The solenoid rod is mounted for linear longitudinal movement and terminates in a solenoid comprising a coil 23 and a slidable armature 24 having an outwardly flared ramp end 25.

Referring to Figures 1 and 4, when the main switch 30 is manually closed it brings the solenoid in circuit with battery 31 to energize the solenoid to move the solenoid armature 24 and solenoid rod 20 linearly to the right, against the action of spring 22. This moves the starter cam 17 and the starter jaw 16 to the right to move the teeth 32 of the starter jaw into slight initial engagement with complementary teeth 33 of the engine jaw 34. This linear movement thus far is caused by energization of the solenoid by direct current and takes place without rotation of the starter motor or its jaw. However, this movement of the solenoid armature 24 has by this time, due to the riding of the arm 29 of plate 28

55 on the flared solenoid armature end 25, made

contact between plate 28 and lead contacts 27 of switch box 26. This brings into circuit with the battery a solenoid which closes contacts in lines L1, L2 and L3 of a three phase alternating current supply 35 which causes the rotation of the starter motor armature 2. The arrangement is thus an interlocking micro switch which effects the rotation of the starter motor armature and starter jaw only after a predetermined extent of starter jaw linear extension by the solenoid 23, 24, and its starter jaw operating rod 20.

Now, referring to Figures 2, 3 and 5, the left portion of the hollow barrel of the starter jaw is partially cut away between its splines to leave the latter extending as prongs. In the example shown, the starter jaw 16 and the cam 17 each have six external spline teeth. As stated before each of the spline teeth of the starter jaw 16 is of less width than that of the space between the internal splines of the planet carrier driving barrel 11 to provide for lost motion therebetween in either rotative direction. Each of the external spline teeth of the cam 17, however, is larger than the spline teeth of the starter jaw 16 and mates, without lost motion, with the internal splines of the driving barrel 11. The spline teeth of the cam 17 are uniform in width but alternately three of them are plain while alternately the other three are provided with longitudinally extending prongs whose side edges are so formed as to provide ramps that are longitudinally inclined with respect to clockwise rotation of the cam 17 as indicated by the arrow in Figures 2 and 3. Normally, as shown in Figure 1, when the starter jaw 16 is in fully retracted position, the ramped prongs of the cam 17 and the prongs of the splined teeth of the starter jaw interlock to bottom therebetween. Figure 5 shows cam 17 to have three alternate plain teeth 36, 37 and 38 and three alternate teeth 39, 40 and 41 with longitudinal prongs 39A, 40A and 41A with inclined ramps 39B, 40B and 41B.

As stated before, the action of the solenoid and solenoid rod is to linearly move the starter jaw and cam forwardly to the right until bare engagement of the starter jaw and engine jaw takes place, at which time the interlocking switch is operated to bring the three phase alternating current supply into circuit to rotate the starter motor and hence the planet carrier barrel 11. Rotation of the cam 17 begins simultaneously, but not rotation of the starter jaw 16, because of the lost motion provided for by the relatively narrow splines on the starter jaw. Figure 2 shows the cam 17 being rotated clockwise in the direction of the arrow relatively to the starter jaw. Four of the six starter jaw splines are shown at 42, 43, 44 and 45. The corresponding internal spline of the driving barrel 11 bears against the upper edge 46 of ramped prong 41 of the cam 17 but in Figure 2 this internal spline of driving barrel 11 has not as yet engaged the upper, or trailing, edge 47 of starter jaw spline 44 and hence the starter jaw is not as yet under rotational drive by barrel 11. With the cam 17 thus under rotational drive, the ramp 41B of spline 41 rides on the upper, or trailing, edge 47 of spline 44 from its position shown in full lines to that shown in dotted lines to effect the longitudinal displacement of the starter jaw and cam shown in dotted lines in Figure 2, the effect of which is to force the starter jaw 16 deeper into engagement with the engine jaw 34. This relative rotation of the cam 17 with the starter jaw 16 continues until the upper, or trailing, edge 46 of cam spline 41 becomes aligned with the

upper, or trailing, edge 47 of starter jaw spline 44, as shown in Figure 3. When this occurs, the starter jaw has been fully extended and meshed with the engine jaw so that the planetary gear 5 carrier driving barrel 11 rotates the cam 17 and starter jaw 16 jointly and consequently the engine jaw 34 at the same speed.

Thus it will be seen that I have provided an engine starting system having interlocked means 10 for positively operating in a definite predetermined sequence of operation whereby adequate starter jaw engagement with the engine jaw is insured before a full speed rotational drive is effected by the starter jaw. Operation of manual switch 30 energizes the solenoid, to be operated by D. C. current, to cause its rod 20 to linearly extend the starter jaw 16, against the influence of spring 22, into slight engagement with the engine jaw. This is strictly a linear movement 15 which may possibly result in a head-on abutment of the ends of the teeth of two jaws, instead of the desired slight initial engagement. After this predetermined distance of linear travel of the solenoid rod the flare 25 of the sliding solenoid 20 armature 24 trips the micro switch to energize 25 the three phase A. C. supply 35 to rotate the starter motor rotary armature 2. This rotates the sun gear 6 and, through the planet system, the driving planet carrier barrel 11 which, in turn, 30 rotates cam 17 without any lost motion.

In contrast to conventional starting systems, the solenoid rod is not fully depended upon to establish jaw mesh and rightfully so because pure linear movement of the starter jaw is too apt to bring about head-on abutment of the jaw teeth, instead of interlocking mesh. The cam and interlocking micro switch are therefore relied upon to establish this final and complete jaw mesh before the driving barrel 11 is in full rotational 35 driving engagement with the starter jaw. As the cam is being fully rotated by the barrel, and before the latter fully engages the trailing edges of the relatively narrower splines of the starter jaw, the cam acts to linearly extend the starter jaw, 40 while at the same time, due to frictional drag, slightly rotates the starter jaw to insure the teeth of the starter jaw being able to interlock those of the engine jaw and avoid head-on abutment and resulting chattering. It follows that upon 45 releasing switch 30 to open the circuit, the solenoid becomes deenergized, spring 22 forces the solenoid rod 20 back to the left, the micro switch is opened, the starter motor stops and the starter jaw resumes its retracted position of Figure 1 to 50 release another manual switch operated engine starting cycle.

I claim:

1. In combination in an engine starter, an electrical rotary driving motor and a source of current for operating the same, a starter jaw and an engine jaw, manual switch operated electrical means for linearly extending said starter jaw into partial mesh with said engine jaw, switch means so arranged with respect to said electrical means as to be automatically operated after a predetermined linear travel of said starter jaw for energizing said motor, a sleeve driven by said motor, said starter jaw being so constructed and arranged with respect to said sleeve as to be driven, with lost motion, by said sleeve, a cam member mounted in said sleeve coaxially with said starter jaw and so-constructed and arranged with respect to said sleeve as to be driven by said sleeve without lost motion, said cam member having cam means so constructed and arranged

with respect to said starter jaw that, upon rotation of said cam by said sleeve, prior to the rotation by the latter of said starter jaw, means are provided to linearly extend said starter jaw into full mesh with said engine jaw prior to full rotative drive of said starter jaw by said sleeve.

2. In combination in an engine starter, an electrical rotary driving motor and a source of current for operating the same, a starter jaw and an engine jaw, manual switch operated electrical solenoid means for linearly extending said starter jaw into partial mesh with said engine jaw, switch means so arranged with respect to said electrical means as to be automatically operated after a predetermined linear travel of said starter jaw for energizing said motor, a sleeve driven by said motor, said starter jaw being so constructed and arranged with respect to said sleeve as to be driven, with lost motion, by said sleeve, a cam member mounted in said sleeve coaxially with said starter jaw and so constructed and arranged with respect to said sleeve as to be driven by said sleeve without lost motion, said cam member having cam means so constructed and arranged with respect to said starter jaw that, upon rotation of said cam by said sleeve, prior to the rotation by the latter of said starter jaw, means are provided to linearly extend said starter jaw into full mesh with said engine jaw prior to full rotative drive of said starter jaw by said sleeve.

3. In combination in an engine starter, an electrical rotary driving motor and a source of A. C. current for operating the same, a starter jaw and an engine jaw, manual switch operated D. C. current electrical means for linearly extending said starter jaw into partial mesh with said engine jaw, switch means so arranged with respect to said electrical means as to be automatically operated after a predetermined linear travel of said starter jaw for energizing said motor by said A. C. current supply, a sleeve driven by said motor, said starter jaw being so constructed and arranged with respect to said sleeve as to be driven, with lost motion, by said sleeve, a cam member mounted in said sleeve coaxially with said starter jaw and so constructed and arranged with respect to said sleeve as to be driven by said sleeve without lost motion, said cam member having cam means so constructed and arranged with respect to said starter jaw that, upon rotation of said cam by said sleeve, prior to the rotation by the latter of said starter jaw, means are provided to linearly extend said starter jaw into full mesh with said engine jaw prior to full rotative drive of said starter jaw by said sleeve.

4. In combination in an engine starter, an electrical rotary driving motor and a source of A. C. current for operating the same, a starter jaw and an engine jaw, manual switch operated D. C. current electrical solenoid means for linearly extending said starter jaw into partial mesh with said engine jaw, switch means so arranged with respect to said electrical means as to be automatically operated after a predetermined linear travel of said starter jaw for energizing said motor by said A. C. current supply, a sleeve driven by said motor, said starter jaw being so constructed and arranged with respect to said sleeve as to be driven, with lost motion, by said sleeve, a cam member mounted in said sleeve coaxially with said starter jaw and so constructed and arranged with respect to said sleeve as to be driven by said sleeve without lost motion, said cam member having cam means so constructed

and arranged with respect to said starter jaw that, upon rotation of said cam by said sleeve, prior to the rotation by the latter of said starter jaw, means are provided to linearly extend said starter jaw into full mesh with said engine jaw prior to full rotative drive of said starter jaw by said sleeve.

5. In combination in an engine starter, an electrical rotary driving motor and a source of current for operating the same, a starter jaw and an engine jaw, manual switch operated electrical means for linearly extending said starter jaw into partial mesh with said engine jaw, switch means so arranged with respect to said electrical means as to be automatically operated after a predetermined linear travel of said starter jaw for energizing said motor, an internally splined sleeve driven by said motor, said starter jaw having external splines to mate, with lost motion, with the splines of said sleeve, a cam mounted in said sleeve coaxially with said starter jaw and having external splines to mate directly with those of said sleeve without lost motion, said cam member having cam means so constructed and arranged with respect to said starter jaw that, upon rotation of said cam by said sleeve, prior to the rotation by the latter of said starter jaw, means are provided to linearly extend said starter jaw into full mesh with said engine jaw prior to full rotative drive of said starter jaw by said sleeve.

6. In combination in an engine starter, an electrical rotary driving motor and a source of current for operating the same, a starter jaw and an engine jaw, manual switch operated electrical solenoid means for linearly extending said starter jaw into partial mesh with said engine jaw, switch means so arranged with respect to said electrical means as to be automatically operated after a predetermined linear travel of said starter jaw for energizing said motor, an internally splined sleeve driven by said motor, said starter jaw having external splines to mate, with lost motion, with the splines of said sleeve, a cam mounted in said sleeve coaxially with said starter jaw and having external splines to mate directly with those of said sleeve without lost motion, said cam member having cam means so constructed and arranged with respect to said starter jaw that, upon rotation of said cam by said sleeve, prior to the rotation by the latter of said starter jaw, means are provided to linearly extend said starter jaw into full mesh with said engine jaw prior to full rotative drive of said starter jaw by said sleeve.

7. In combination in an engine starter, an electrical rotary driving motor and a source of current for operating the same, a starter jaw and an engine jaw, manual switch operated electrical means for linearly extending said starter jaw into partial mesh with said engine jaw, switch means so arranged with respect to said electrical means as to be automatically operated after a predetermined linear travel of said starter jaw for energizing said motor, an internally splined sleeve driven by said motor, said starter jaw having external splines to mate, with lost motion, with the splines of said sleeve, a cam mounted in said sleeve coaxially with said starter jaw and having external splines to mate directly with those of said sleeve without lost motion, said cam and starter jaw having loosely interlocking end prongs, inclined ramps on the side edges of said cam prongs so constructed and arranged with respect to said starter jaw that, upon rotation of said cam by said sleeve, prior to the rotation by the latter of

said starter jaw, means are provided to linearly extend said starter jaw into full mesh with said engine jaw prior to full rotative drive of said starter jaw by said sleeve.

8. In combination in an engine starter, an electrical rotary driving motor and a source of A. C. current for operating the same, a starter jaw and an engine jaw, manual switch operated D. C. current electrical means for linearly extending said starter jaw into partial mesh with said engine jaw, switch means so arranged with respect to said electrical means as to be automatically operated after a predetermined linear travel of said starter jaw for energizing said motor by said A. C. current supply, an internally splined sleeve driven by said motor, said starter jaw having external splines to mate, with lost motion, with the splines of said sleeve, a cam mounted in said sleeve coaxially with said starter jaw and having external splines to mate directly with those of said sleeve without lost motion, said cam and starter jaw having loosely interlocking end prongs, inclined ramps on the side edges of said cam prongs so constructed and arranged with respect to said starter jaw that, upon rotation of said cam by said sleeve, prior to the rotation by the latter of said starter jaw, means are provided to linearly extend said starter jaw into full mesh with said engine jaw prior to full rotative drive of said starter jaw by said sleeve.

9. In combination in an engine starter, an electrical rotary driving motor and a source of A. C. current for operating the same, a starter jaw and an engine jaw, manual switch operated D. C. current electrical solenoid means for linearly ex-

tending said starter jaw into partial mesh with said engine jaw, switch means so arranged with respect to said electrical means as to be automatically operated after a predetermined linear travel of said starter jaw for energizing said motor by said A. C. current supply, an internally splined sleeve driven by said motor, said starter jaw having external splines to mate, with lost motion, with the splines of said sleeve, a cam mounted in said sleeve coaxially with said starter jaw and having external splines to mate directly with those of said sleeve without lost motion, said cam and starter jaw having loosely interlocking end prongs, inclined ramps on the side edges of said cam prongs so constructed and arranged with respect to said starter jaw that, upon rotation of said cam by said sleeve, prior to the rotation by the latter of said starter jaw, means are provided to linearly extend said starter jaw into full mesh with said engine jaw prior to full rotative drive of said starter jaw by said sleeve.
